UNITED STATES PATENT OFFICE.

OVILA W. BOYEA, OF BARRE, VERMONT.

AEROPLANE.

Application filed March 10, 1921. Serial No. 451,177.

To all whom it may concern:

Be it known that I, OVILA W. BOYEA, a citizen of the United States, and a resident of Barre, in the county of Washington and 5 State of Vermont, have invented a new and Improved Aeroplane, of which the following is a full, clear, and exact description.

Among the principal objects which the present invention has in view are: to increase 10 the levitation of an aeroplane; to vary the levitation in correspondence with the speed of the plane; to increase the support of a plane and parts connected therewith when falling.

15

Drawings.

Figure 1 is a top plan view of an aeroplane constructed and arranged in accordance with the present invention.

20 Figure 2 is a vertical longitudinal section taken on the line 2—2 in Fig. 1.

Figure 3 is a vertical cross section of the plane, the section being taken on the line 3—3 in Fig. 2.

25 Figure 4 is a vertical longitudinal section showing a modified form of the carrying plane with controls therefor, and a fragment then modified form of the aeroplane.

Figure 5 is a similar view showing a further modified form of the aeroplane.

Description.

As seen in the drawings the carrying plane 11 is fixedly mounted in permanent relation 35 to the fuselage 12 and is supported from the curved top 13 a distance much greater than usually employed. The curvature of the top 13 which corresponds to the camber of the usual construction is platted substantially as shown in Fig. 2 of the drawings to 40 present a relatively blunt nose or forward edge and a trailing or rearwardly extended apron portion 14. In plating the curve of the top 13—14 there is an endeavor to establish 45 a correspondence with the stream line of the air or atmosphere which is displaced by the forward portion of the top 13.

In the preferred form as shown in Figures 1, 2 and 3, the carry plane 11 is supported from the top 13 and the apron 14 thereof, and the lower rear edge 15 of the carry plane is also disposed slightly below and at a distance from the rear edge 16 of the apron 14. The disposition of the edges 50 15 and 16 are also esteemed in correspondence

with the stream of air displaced by the carry plane 11, which spills from the edge 15 to impinge upon the undersurface of the aprons 14 adjacent the edge 16 thereof. The stream-line of the air spilled from the plane 11 to where it impinges on the apron 14 varies in correspondence with the speed of the plane, that is to say, the greater the speed of the plane, the smaller the affected area of the apron 14. It is the intention that 55 at all times and at all speeds some portion of the apron 14 adjacent the trailing edge 16 shall be impinged by the air spilled from the plane 11 to steady the plane in its operation. This also compensates for the variation in the speeds of the plane by diminishing the lifting surface at high rates of speed and increasing the lifting surface at low rates of speed.

The motive power including a propeller 17 75 and suitable prime mover for driving the same together with the controls of the plane in flight are those usually employed in airplanes and of suitable construction. The controls referred to include the dirigible 80 rudder 18, the levitation rudders 19, and ailerons 20. As shown in the drawings the ailerons are mounted upon and located at the extremities of the carry plane 11.

When a plane, constructed in accordance 85 with the preferred form as shown in Figures 1 to 3 inclusive, is in service, the air through which the plane is moving and which is passing from the rear edge 15 of the plane 11 operates to withdraw from the 90 pocket 21, or the space between the top 13 and the plane 11, a certain proportion of the air normally contained therein. The air which remains within the pocket 21 is comparatively rarefied and the combined weight 95 of the structure and contained air is reduced. This appreciably increases the levitation of the airplane in service.

It is obvious that as the speed of the plane is increased the suction is increased and the 100 remaining air is further rarefied. The pocket 21 and the apron 14 is utilized as a safety factor in case of accident as when the machine starts to fall by reason of failure of power or engine trouble, the aviator 105 may take advantage of the open structure to utilize the pocket 21 and the overhang of the apron 14 as a parachute to retard the speed of a fall. This principle may be largely used in landing by permitting in the 110

last stages of the landing the machine to settle under the supporting influence of the pocket 21 and apron 14.

In Figures 4 and 5 are shown modifications of the preferred construction. The modification shown in Fig. 4 provides for substituting for the apron portion 14 of the preferred form a movable apron. As seen in the drawings the portion 22 is supported 10 by struts 23 which form the frame that is pivoted on a shaft 24 that extends cross-wise of the machine. The disposition of the apron 22 is regulated by means of a lever 25 that is pivoted at 26 and guided by 15 a quadrant 27. The hand hold 28 is available to the operator of the machine while the rear end of the lever 25 is connected by means of a link 29 with the rearward portion of the apron 22. As the lever 25 is 20 rocked the apron 22 is lifted to swing around the shaft 24 to depress or elevate the rearward edge of the said apron, thereby increasing the levitation power of the machine.

25 In the modified form of the invention shown in Fig. 5 of the drawing, an auxiliary carrying plane 30 is provided which is hinged at 31 co-incident with the rear edge of the apron 14. The mechanism for changing 30 the angle of the plane 30 is the same as that described with reference to the mechanism for handling the apron 22, of the construction shown in Fig. 4 of the drawings. It will be noted, however, that when 35 employing the construction shown in Fig. 5 of the drawings the supporting surface of the plane 30 is considerably augmented and operates in conjunction with the plane 11. Also as shown by dotted lines in Fig. 5 of 40 the drawings when the plane 30 is lifted the pocket 21 may be employed as above described with reference to the preferred construction shown in Figures 1 to 3 inclusive.

When using this form of the invention it 45 will be understood that the aviator may by

lifting the forward edge of the plane 30 avail himself of the dragging effect of the apron 14, or when falling, may avail himself of the supporting effect of the pocket 21.

Claims.

50

1. An aeroplane having a carrying plane inclined forwardly to the line of flight, and a curved top inclined rearwardly from the line of flight, the rear edges of said carry 55 plane and top being spaced apart to form a rearwardly opening pocket; and an apron extending from said top to a distance in the rear of said carry plane for cooperating with said carry plane to support the load 60 of said aeroplane.

2. An aeroplane having a carrying plane inclined forwardly to the line of flight, and a curved top inclined rearwardly from the line of flight, the rear edges of said carry 65 plane and top being spaced apart to form a rearwardly opening pocket; an apron extending from said top to a distance in the rear of said carry plane for cooperating with said carry plane to support the load 70 of said aeroplane; and means for varying the disposition of said apron for varying the exposed area thereof.

3. An aeroplane having a carrying plane inclined forwardly to the line of flight, and 75 a curved top inclined rearwardly from the line of flight, the rear edges of said carry plane and top being spaced apart to form a rearwardly opening pocket; an apron extending from said top to a distance in the 80 rear of said carry plane for cooperating with said carry plane to support the load of said aeroplane; and means for varying the disposition of said apron for varying the exposed area thereof, said means embodying 85 hand-controlled mechanisms adapted for manipulation by the operator of the aeroplane.

OVILA W. BOYEA.
